US00D607315S

(12) **United States Design Patent**
George et al.

(10) **Patent No.:** US D607,315 S
(45) **Date of Patent:** ** Jan. 5, 2010

(54) **CONTAINER AND LID**

(75) Inventors: **Roberta S. George**, Lititz, PA (US);
Michael D. Handler, Bethel, CT (US);
Nicolas Bouveret, St Placide (CA)

(73) Assignee: **BC-USA**, New Holland, PA (US)

(**) Term: **14 Years**

(21) Appl. No.: **29/327,255**

(22) Filed: **Nov. 3, 2008**

(51) LOC (9) Cl. **09-03**

(52) U.S. Cl. **D9/420; D9/428**

(58) **Field of Classification Search** D9/420,

D9/423, 425, 428, 429, 447, 449, 504; D7/629;
220/780-795, 212, 252, 558, 810; 206/37,

206/38, 235; 222/480, 556, 563, 572; 229/124

See application file for complete search history.

(57) **CLAIM**

The ornamental design for a container and lid, as shown and described.

DESCRIPTION

FIG. 1 is a top, right, front perspective view of a container and lid according to our design;

FIG. 2 is a top plan view thereof;

FIG. 3 is a bottom view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top, right, front perspective view showing an alternate position of the container lid;

FIG. 9 is a top, right, front perspective view of the container shown without the lid for clarity of detail according to our design;

FIG. 10 is a top plan view thereof;

FIG. 11 is a bottom view thereof;

FIG. 12 is a front elevational view thereof;

FIG. 13 is a rear elevational view thereof;

FIG. 14 is a left side elevational view thereof; and,

FIG. 15 is a right side elevational view thereof.
